Fig. 1.

Fig. 2.

Fig. 3.

Fig. 4.

FIG. 1 is a top plan view of a lavatory showing my new design.

FIG. 2 is a front elevational view thereof.

FIG. 3 is a side elevational view thereof.

FIG. 4 is a cross-sectional view taken on line 4—4 of FIG. 2.

The characteristic feature of my design resides in the graining striations which radiate from one side of the drain outlet towards a front corner. Along this path the striations curve away successively in opposite directions towards the corner diametrically opposite to said front corner.

I claim:

The ornamental design for a lavatory or similar article, as shown and described.
